LOCK ESCUTCHEON

Benjamin M. Levinger, Hillsborough, Calif., assignor to
Schlage Lock Company

Filed Sept. 6, 1966, Ser. No. 3,741

Term of patent 14 years

(Cl. D50—6)

FIG. 1

FIG. 3

FIG. 4

FIG. 2

FIG. 5

FIG. 6

FIGURE 1 is a front elevation of the lock escutcheon showing my new design;

FIGURE 2 is a rear elevation of the article of FIGURE 1;

FIGURE 3 is a side elevation of the article of FIGURE 1;

FIGURE 4 is a cross section through the article of FIGURE 1, the plane of section being indicated by the line 4—4 of FIGURE 1;

FIGURE 5 is a top plan of the article of FIGURE 1; and

FIGURE 6 is a bottom plan of the article of FIGURE 1.

I claim:

The ornamental design for a lock escutcheon, as shown.
